UNITED STATES PATENT OFFICE.

JOSEPH A. GUYER, OF MARION, INDIANA.

ELECTRIC IRON.

1,353,471.

Specification of Letters Patent. Patented Sept. 21, 1920.

Application filed March 24, 1919. Serial No. 284,698.

To all whom it may concern:

Be it known that I, JOSEPH A. GUYER, a citizen of the United States, residing at Marion, in the county of Grant and State 5 of Indiana, have invented certain new and useful Improvements in Electric Irons; and I do hereby declare the following to be a full, clear, and exact description of the invention, such as will enable others skilled 10 in the art to which it appertains to make and use the same.

The present invention relates to sad irons, and more especially to electric irons, and aims to provide such a device comprising a 15 novel construction and assemblage of the component elements, to enhance the efficiency of the iron, to enable it to be readily taken apart and the heating unit renewed quickly, and to provide other advantages.

20 One of the objects of the invention is the provision of such an iron composed of a main block or casting with which the electric heating unit is assembled in a novel manner, to efficiently heat the face of the iron, 25 and to also provide for the ready removal and replacement of the resistance wire when burnt out.

30 A further object is the novel assemblage of the top or cover with the body or main part of the iron, to provide for simplicity in construction and efficiency.

A still further object is the provision of novel means for the connection of the electrical conductors with the heating unit.

35 With the foregoing and other objects in view which will be apparent as the description proceeds, the invention resides in the construction and arrangement of parts hereinafter described and claimed, it being understood that changes can be made within 40 the scope of what is claimed without departing from the spirit of the invention.

The invention is illustrated in the accompanying drawings, wherein:—

45 Figure 1 is a plan view of the iron with the cover removed.

Fig. 2 is a longitudinal vertical section, portions being shown in elevation.

Fig. 3 is a cross section taken on the line 50 3—3 of Fig. 2.

Fig. 4 is a plan view of the body or block of the heating unit.

55 The body or main part of the iron, which is preferably a metal casting, comprises a base plate 1, the lower surface of which provides the face of the iron, and a block 2

upstanding from the plate 1, and of smaller outline, so that the edges of said plate extend from the block 2. The block 2 is shorter than the plate 1 and is provided at 60 its forward end with a reduced extension 3 projecting toward the point or forward end of the plate 1. The block 2, in order to accommodate the heating unit, is provided with a longitudinal tunnel or opening 4 65 therethrough from end to end, and extending under the extension 3. This tunnel 4 is relatively wide so as to extend over a relatively large portion of the plate 1, but is of small height, being immediately over the 70 plate 1 so as to be close to the face of the iron.

The heating unit of the iron embodies a plate or flat block 5 of porcelain or similar insulating material, which is slipped longitudinally into the tunnel 4 with its ends protruding from the ends of the tunnel, and the forward end of the plate 5 has a reduced extension 6 projecting below the extension 3. This plate 5 is therefore disposed over the 80 plate 1 throughout the greater portion of the area thereof, excepting at the edges of the plate 1, and close to the face of the iron. This plate 5 fits snugly within the tunnel and remains in place after once being inserted, excepting for purpose of removal when broken, which is not apt to occur. The plate 5 is provided with longitudinal bores or passages 7, some of which extend through the extension 6, and a resistance wire 8 extends longitudinally back and forth through the bores 7, and is preferably coiled. This wire can be readily inserted back and forth through the plate 5, and when burnt out can be readily pulled out of the plate 5 for the 95 insertion of a new wire, which will require but a few minutes' time.

In order to connect the electrical conductors or wires with the heating unit, a binding post bracket 9 is attached to the 100 rear end of the block 2, this bracket being formed of a sheet of insulating material, and being seated within an upper recess 10 in the block 2 near the rear end thereof and made secure by means of screws 11 or the 105 like. The bracket 9 has an offset portion 12 at its rear end provided with depending ears 13 extending within a recess 14 in the rear end of the block 2, and said ears 13 have binding posts 15 to which the terminals of the wire 8 are clamped by the nuts on said posts. The binding posts 15 are

opposite to and in alinement with one another, and parallel binding posts 16 are engaged through the offset portion 12 and are connected to the respective binding posts 15 by jumper wires 16'. The binding posts 16 have the outstanding contact fingers 17 for the slip connection of a coupling, to electrically connect the usual cord or wires with the iron, as well known. In renewing the 10 resistance wire 8, the terminals thereof are disconnected from the binding posts 15, and when the new wire is inserted, it is only necessary to connect the ends thereof to said binding posts, which can be conveniently 15 done at the outside of the bracket 9, the connections on the interior of said bracket being permanent.

The cover or top 18 of the iron, which can be of pressed sheet metal, surrounds 20 and extends over the block 2, and has its edge extending downwardly to seat on the edge portion of the plate 1 around the block 2 thereof. In order to prevent displacement of the body and cover, studs 19 25 are set in the plate 1 at the three corners thereof, as seen in Fig. 1, and said studs 19 stand from the plate 1 and have their sides cut or filed away, as at 20, to fit snugly within the corners of the cover 18. Therefore, when the cover is slipped down on the 30 body, the corners thereof snugly fit the studs 19, thereby preventing the cover and body from shifting out of place. The cover is provided at the top with a longitudinal 35 depression 22 in which the lower portion of the handle 23 is seated, and a clamping screw 24 extends downwardly through the lower portion of the handle 23 and through the depression 22 into a threaded socket in 40 the block 2, thereby clamping the handle on the cover, and at the same time, clamping the cover on the body with a single securing element. The rear portion of the cover 18 has an outstanding neck 21 surrounding the 45 fingers 17 to receive the coupling or plug that engages the fingers 17. With the present construction, the main part of the iron is integral and comprises a single casting, including the plate 1 and block 2, and the 50 heating unit is close to the face of the iron, so that the heat will be efficiently transmitted to said face. By the provision of the plate 5 through which the resistance wire extends, with said plate located close to the

face of the iron, the iron is heated efficiently, without the objections resulting from the use of mica as now used in electric irons between sheets of which the resistance unit is usually disposed, and around which the resistance wire is usually wound which 60 separates the same into upper and lower portions. Furthermore, the present construction is simple, and permits of repairs being made quickly.

Having thus described the invention, 65 what is claimed as new is:—

1. An electric iron comprising a base plate having an upstanding block of smaller outline, said block having a tunnel therethrough adjacent to said plate, a plate of insulating material extending through said tunnel and having bores extending therethrough, a resistance wire extending back and forth through said bores and extending from each bore to the next beyond the ends 75 of the bores and being removable from said bores, and a cover surrounding said block and plate of insulating material and seated on the base plate.

2. An electric iron embodying a metallic 80 block having a tunnel, an insulating plate extending within said tunnel and having bores, a resistant wire extending back and forth through said bores, an insulating bracket secured on said block at one end of 85 the tunnel and having an offset portion overhanging said end of the tunnel, the corresponding end of the block having a recess, and said bracket having ears below 90 said offset portion disposed in said recess, binding posts extending through said ears for the connection of the terminals of said wire at the outer sides of the ears, binding posts carried by said offset portion and having upwardly extending contact fingers at 95 right angles with the first named binding posts, and electrical connections between the first named and second named binding posts between said ears and under said off- 100 set portion.

In testimony whereof I have signed my name to this specification in the presence of two subscribing witnesses.

JOSEPH A. GUYER.
